COMBINED SCORE KEEPER AND RING TOSS
GAME DEVICE OR SIMILAR ARTICLE

Lawrence Jonesi, Chicago, Ill.

Application April 14, 1954, Serial No. 29,994

Term of patent 14 years

(Cl. D34—5)

FIG. 1

FIG. 2

FIG. 3.

Fig. 1 is a front elevational view of a combined score keeper and ring toss game device or similar article, showing my new design;

Fig. 2 is a front perspective view thereof with the ring thereon; and

Fig. 3 is a rear elevational view thereof.

The dominant features of my new design are shown in solid lines in the drawing.

I claim:

The ornamental design for combined score keeper and ring toss game device or similar article, as shown and described.
